to American Engineering Company, Philadel-
phia, Pa., a corporation of Pennsylvania

Application July 8, 1931. Serial No. 549,548

6 Claims. (Cl. 257—249)

This invention relates to improvements in refrigerating apparatus, and has for a principal object the provision of a highly efficient, simply constructed cooling unit of a character adapted to replace to advantage the cooling coils of refrigerating systems.

Still another object of the invention is to provide a device of the stated character in the form of a standardized unit of novel form which is adapted for use individually or in association with one or more like units to provide the necessary refrigeration.

A further object of the invention is to provide a refrigerating unit of the stated character so constructed as to afford a relatively short gas travel and having a correspondingly relatively rapid heat dissipation factor.

A still further object is to provide means for compensating uneven expansions and contractions in the structure of the unit to avoid damage from that cause.

A still further object is to provide a refrigerating unit adapted for immersion in a cooling bath and when so immersed for circulation therethrough of a fluid to be cooled, whereby a highly efficient transfer of heat from the said fluid to the cooling medium is obtained.

The invention further resides in certain novel and advantageous structural features and details hereinafter set forth and illustrated in the attached drawings, in which:

Figure 1 is a view in perspective of a unit made in accordance with our invention;

Fig. 2 is a longitudinal sectional view of a portion of the unit;

Fig. 3 is a plan view of an assembly of units showing the preferred method of interconnection;

Fig. 4 is an end view of the assembly illustrated in Fig. 3;

Fig. 5 is a fragmentary sectional view similar to Fig. 2 but illustrating a preferred construction;

Fig. 6 is a view similar to Fig. 5 illustrating a further embodiment of the invention;

Fig. 7 is an end elevational view of a unit illustrating a detailed modification within the scope of the invention, and

Fig. 8 is a fragmentary view illustrating one preferred method of connecting the units in series with the grids placed end to end.

With reference to the drawings, our device in a desirable form comprises a double-walled preferably cylindrical casing 1, said walls being joined together at their extremities to form an outer annular chamber 2, of relatively small capacity,

and an inner chamber 3 the ends of which in the present instance are defined by heads 4 secured in the ends of the casing. One or both of the heads 4 is provided with a tapped aperture 5 affording access to the inner chamber and normally closed by plugs 5a. The outer chamber 2 is provided at each end with a pair of ports, 6, 6 and 7, 7, respectively, in the outer casing wall 8, the ports of each pair in the illustrated embodiment being oppositely arranged and providing for connection of the unit in a refrigerating system and to like units, as hereinafter described. Directly opposite the ports 6 and 7, the inner wall 9 of the casing is provided with a circumferential depression or recess 11 which has the effect of enlarging the chamber 2 at those points, the function of these recesses being set forth hereinafter. The outer casing wall 8 is provided with a series of radially projecting fins 12, preferably of sheet metal of the same character as the metal used in the casing walls 8 and 9. These fins are in close frictional engagement with the outer surface of the wall 8, the joint being such as to provide an unobstructed heat-conducting path between the fins and the casing.

In constructing the device as described above, the outer and inner walls 8 and 9 and the heads 4 may be secured together at their extremities by means of welding, fittings 13, 13 and 14, 14 being welded into apertures in the outer casing wall 8 and defining the ports 6, 6 and 7, 7. These fittings are tapped for reception of pipes 15, plugs 16 or other fittings as the case may be. Prior to the welding in of the fittings 13 and 14, the fins 12 are applied to the outer casing member 8, preferably by means of suitable presses of high power. As shown in Fig. 2, each of the fins is provided with a central opening defined by a transversely projecting flange 17, this opening being originally slightly smaller in diameter than the outer circumference of the outer casing member 8, and in assembly the flanges 17 seat firmly throughout their entire inner circumferential area on the said member 8.

In practice, the unit described above may be used alone or in conjunction with other like units. Where used alone, the unit is connected in a suitable refrigerating system through the medium of the pipes 15 which respectively enter one of the ports of the two sets 6 and 7. For dry gas systems, it is preferred to introduce the refrigerant at one end through the nether port and to withdraw the gas at the opposite end from an upper port. For flooded systems, the refrigerant may to advantage be introduced into the

bottom of the unit and withdrawn from the top, or it may be introduced in the top at one end and withdrawn from the top at the other end. The others of the ports are in each instance closed by means of the plugs 16. The refrigerant entering, say the lower port 13, expands immediately and rapidly in the enlarged space provided by the recesses 11 in the inner casing wall 9 and passes longitudinally through the chamber 2 to the port 7 at the opposite end of the casing, from which it discharges through the pipe 15 connected thereto. Heat is absorbed through the outer casing walls 8 to which it is conducted readily through the heat-conducting fins 12 and through the inner wall 9.

The interior chamber 1 is adapted to receive a suitable brine from which heat is also extracted by the expanded refrigerant passing through the chamber 2, this body of brine in the inner chamber thereby constituting in effect a reservoir for cold which is effective for a given period of time following interruption of the refrigerating cycle. Preferably the brine is such as to freeze at the refrigerated temperatures. In effect, the cold is stored in the body of brine within the inner chamber 3, which thereby is made to constitute a potential source of refrigeration in the event of interruption of the flow of the refrigerant in the outer chamber, as set forth above.

Where a plurality of the units is required for a desired refrigerating capacity, the units preferably are secured in banks or sets after the manner illustrated in Figs. 3 and 4. It will be noted that the units are connected in the refrigerating system in parallel, the one end of each of the units being connected to the supply pipe 18, and the refrigerant discharging directly from each unit to the return pipe 19. Following introduction of the refrigerant to any one of the interconnected units, the shortest possible path for the expanded gases to the discharge pipe 19 is provided. Dissipation of heat through the medium of the refrigerant is, therefore, constantly at a maximum, and the efficiency of the assembly is correspondingly high. The units may be connected in series if desired, and when so joined in end to end relation, the method shown in Fig. 8 is preferred. In this instance, the two upper and two lower ports of the adjoining units are connected by the pipes 24 and 25 so that a path is provided for the refrigerant whether in the gaseous or liquid state or in both. Obviously, other methods of connecting the units in series may be employed without departing from the invention. The unit is adapted for use either in a full flooded or dry gas system.

A unit made in accordance with our invention preferably is composed of seamless steel tubing with fins of the same metal to avoid different coefficients of expansion and electrolytic action tending to interfere with an efficient heat-conducting joint between the casing members and the fins. The device has an extremely low manufacturing cost and a relatively high refrigerating efficiency. Particular attention is directed to the fact that by use of the double-walled casing and the passage of the refrigerant through an annular chamber of relatively small capacity rather than through a simple tube, as has been general practice in the past, the effective refrigerating surface of the casing is made relatively great as compared with the necessarily small quantity of the circulating refrigerant at any

moment occupying the chamber 2, and the efficiency is thus relatively high.

In Fig. 5, we have illustrated a preferred form of refrigerating unit made in accordance with our invention. In this instance, it will be noted that the port in the head 4a is relatively large, embracing a major portion of the area of the head. This port is normally closed, in the illustrated embodiment, by a socketed screw plug 5b. The construction has a practical advantage in the step of manufacture that involves the immersion of the unit in a galvanizing bath, in that it affords ready admission for the galvanizing fluid to the interior chamber 3 of the unit and avoids unequal expansions of the outer and inner shells due to unequal heating in the galvanizing bath. In this embodiment, it will also be noted that we have provided an additional circumferential recess 11a intermediate the ends of the unit in addition to the circumferential depressions 11 opposite the jacket ports. These circumferential recesses 11, in addition to affording a relatively large chamber at the said ports for reception of the refrigerating medium, function also as a means for preventing damage to the units due to unequal expansions of the inner and outer shells. The recess 11a affords a further safeguard in this respect, and one or more may profitably be included in positions intermediate the ends of the unit. In this instance also, as in the previously described embodiment, the fins 12 are provided at each side with apertures 21 (see Fig. 1) affording a desirable means for suspending the units from a suitable support and providing for insertion of reinforcing rods or elements where the fins are of such size or the units are of such length as to require this additional reinforcing or rigidifying means. These apertures are also useful for attaching baffles and drip pans.

While the embodiments shown in Figs. 1 to 5, inclusive, make provision for an interior chamber which may to advantage be used as a receptacle for a brine or the like as previously described, it has been found that by eliminating the heads 4 or 4a, see Fig. 6, the units described above may be used with great efficiency in the refrigerating of gases or liquids circulated through the units from one end to the other or in which the units are immersed. The double wall construction has a particular utility in this respect, in that it provides for extensive effective refrigerating surfaces for contact with the circulating gases or liquids to be cooled. In all other respects, the unit shown in Fig. 6 is similar to those previously described.

This same form of unit may be used with high efficiency to cool a fluid circulated through the annular chamber 2, the unit being immersed in a chilled brine or other cooling medium.

Where the units are required to be mounted in restricted spaces or in close proximity to a wall or partition, the form shown in Fig. 7 will be found of advantage. The fins 12a are in this instance reduced in the vertical dimension providing a relatively flat form, and in order further to economize in space, the inlet and discharge fittings 22 and 23 are made to extend horizontally from the upper and lower sides of the tubular casing as illustrated.

A refrigerating unit made in accordance with our invention has certain highly desirable operating characteristics not present in refrigerating units of the prior practice. By employing a brine chamber for storage of cold as previously

described, the number of cycles of operation of the unit in any given application and over a given period of time is reduced, this effecting an economy in the operating expenses and also increasing the useful life of the apparatus by eliminating wear and tear in the control elements.

This feature is of particular utility in systems where a temperature must be maintained between small limits of variation, since it avoids to a large extent the constant starting and stopping of the refrigerating mechanism normally required to maintain a substantially constant temperature. The incorporation of the brine chamber has a further utility in systems including units mounted in separate chambers wherein the temperature of both chambers is controlled by a thermostat mounted in one of the chambers only. The brine chamber in such case has a carry-over effect for the chamber lacking the thermostat under circumstances where the temperature in the latter chamber tends to rise while the temperature in the other chamber remains below the thermostat-actuating point. The jacketed form of casing also effects a considerable economy, in that it requires as compared with the single tubular form of unit a relatively small quantity of refrigerant for a relatively extended effective refrigerating area. It has further been found that as between these two types of refrigerating unit, that made in accordance with our invention affords the greater general efficiency.

There may be considerable modification in the structural form of the device without departing from the principles of the invention.

We claim:

1. A refrigerating unit comprising a plurality of hollow cylindrical casings, adapted for substantially horizontal installation, and fittings at the ends of said casings defining intake and discharge ports, different ones of said fittings communicating with upper and lower portions of the casings and extending therefrom in the transverse direction, said fittings being so constructed and arranged that said casings may be connected either in series or in parallel.

2. A refrigerating unit comprising a plurality of hollow casings, and fittings defining intake and discharge ports therefore, said ports entering said casings on opposite sides of a plane longitudinally intersecting said casings, said fittings extending from the casings in directions substantially parallel to said plane, said fittings being so constructed and arranged that said casings may be connected either in series or in parallel.

3. A refrigerating unit comprising a pair of cylinders of differing diameters arranged one

within the other and joined at their extremities to form an annular longitudinal chamber, means for circulating a refrigerating medium through said chamber, at least one of said cylinders having a circumferential corrugation to compensate for differing longitudinal expansions of said cylinders, and a plurality of projecting fins arranged in longitudinal series on said outer cylinder, a plurality of said fins having apertures in alignment longitudinally of said cylinders for insertion of reinforcing rods.

4. A refrigerating unit comprising a plurality of pairs of cylinders, the cylinders of each pair being of different diameters and arranged one within the other and joined at their extremities to form an annular longitudinal chamber, the inner cylinder of each pair having a circumferential corrugation to compensate for differing longitudinal expansions of said cylinders, a plurality of projecting fins arranged in longitudinal series on the outer cylinder of each pair, fittings defining intake and discharge ports provided on the outer cylinder of each pair, and means for circulating a refrigerating medium through the annular chamber defined by each of said pairs of cylinders, said fittings being so constructed and arranged that said pairs of cylinders may be connected either in series or in parallel.

5. A refrigerating unit, comprising a hollow casing, fittings defining intake and discharge ports therefor, a plurality of projecting fins arranged in longitudinal series on said casing, said fins being provided with a flange which seats tightly against the outer surface of said casing, and apertures provided in said fins in alignment longitudinally of said cylinders for insertion of reinforcing rods.

6. A refrigerating unit, comprising a pair of metallic cylinders of different diameters arranged one within the other, and joined at their extremities to form an annular longitudinal chamber, fittings provided on said outer cylinder defining intake and discharge ports, means for circulating a refrigerating medium through said annular chamber, a series of projecting fins arranged in longitudinal series on said outer cylinder, each of said fins being provided with an annular flange which seats tightly against the outer surface of said outer cylinder, said inner cylinder being open at the ends, said cylinders and fins being galvanized to prevent the formation of rust thereon, and to maintain intimate contact between the fins and cylinder.
